SPLIT BACK-UP FLANGE MEMBER

John K. Vitas, 11650 SW. Ridgeview Terrace,
Beaverton, Oreg. 97005

Filed Aug. 25, 1971, Ser. No. 175,025

Term of patent 14 years

Int. Cl. D8—08

U.S. Cl. D8—236

FIG. 1

FIG. 3

FIG. 2

FIG. 4

FIG. 1 is an inner face view of a split flange member of my invention;

FIG. 2 is an outer face view taken from the opposite side;

FIG. 3 is an edge view of the split flange member taken in the direction of the right edge of FIG. 1;

FIG. 4 is an edge view of the split flange member taken upwardly of FIG. 2 as the parts are shown in the drawings.

I claim:

The ornamental design for a split back-up flange member, as shown.
